Primary Examiner — Marissa J. Cash*Assistant Examiner* — Earl B Elowsky(74) Attorney, Agent, or Firm — Westbridge IP LLC(57) CLAIM

The ornamental design for a portable bidet, as shown and described.

DESCRIPTION

FIG. 1 is a top perspective view of a portable bidet, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a closed state view thereof;

FIG. 10 is an enlarged detail view of area 10 in FIG. 1; and, FIG. 11 is an enlarged detail view of area 11 in FIG. 3.

The broken lines in the drawings illustrate the portions of the portable bidet, which form no part of the claimed design. The dash-dot-dash broken lines encircling the enlarged views are for annotative purposes only and form no part of the claim thereof.

1 Claim, 11 Drawing Sheets(56)
